UNITED STATES PATENT OFFICE

GUSTAV A. BOETTCHER, OF NEW YORK, N. Y.

LOOPING DEVICE

Application filed May 7, 1927. Serial No. 189,680.

This invention relates to looping devices with particular reference to the class wherein the looper proper is secured to an arm which in turn is hinged to a supporting member 5 adapted to be mounted on a shaft in a quilting or sewing machine.

The main object of my invention is to provide quilting and sewing machines with a looper device in which the looper may be unlatched and folded outward to a readily accessible position for rethreading or other attention.

Further objects and the various advantages attained by my invention will appear fully 15 hereinafter as the specification proceeds.

In the drawing forming part hereof,

Fig. 1 is a view which diagrammatically represents the main moving parts of a quilting machine to show the relation of the parts 20 in conjunction with the device embodying this invention.

Fig. 2 is a view of two looper devices mounted on a shaft with the looper arm of one device in open and extended position.

Fig. 3 is a side view of one such device with the arm partly open to show the relation of the same to the latch normally retaining the same in position.

Throughout the views, the same reference 25 numerals indicate the same parts.

In some sewing and quilting machines it is possible to build their structure very compact and do excellent work almost impossible on the ordinary style if the work table or apron 35 may cover the looping devices therein. This introduces a grave difficulty however, as the loopers are then inaccessible. My invention is designed with the object in view of avoiding this point as well as taking in the first 40 object mentioned.

In practice, a work table or apron 1 is spaced between the feed roller 12 and the drawing rollers 9 and 10, while a needle 2 is supported by a bar 3 in a position to pass a 45 distance into the table and carry with it the thread 4. A fabric 11 upon which work is to be done is fed from roller 12 under the needle, which may represent a row of similar needles, and thence through rollers 9 and 10 to a larger take up roller not shown. Below

the table is mounted a swingable looper device on a rockable shaft 13, the body of the device being noted 15, and rockable with the shaft. A block 14 serves to hold the device on the shaft, and if unscrewed from the part 55 15 will release the device from the shaft without dismantling the whole machine. The means for rocking the shaft to operate the looper are not shown, as such means and operations are well known in the art. However, the part 15 has a slot 22 upon one side in which an arm 7 is hinged or pivoted at a point 17 below the shaft 13. And in the normal position, a thread 5 will pass through the looper 6 to mesh with the thread 4 from the 60 needle. The part 8 forms a guide and assists in this operation, although the same is not necessary to mention at length here, as the device as a whole is more directly the subject 65 of this description. 70

The looper arm has a pin 21 projecting over one side of the body part 15 and is adapted to be normally engaged by a latch 20 which is projected outward by a spring indicated at 23 in part 15, while a latch handle 18 is adapted 75 to travel in the slot 19 and incidentally retain the latch member in place. If the thread 5 has broken or is exhausted, and a new thread must be put through the looper, it is manifest that it would be a little difficult to reach the 80 looper under the table with the thread, especially if a series of looper devices were mounted close together on the shaft 13. It is but necessary in this instance to pull down a little on handle 18 to release the arm 7 which 85 may be gripped between the fingers at the finger clearance 16 and the arm will readily fold down into a position noted in the first view by dotted lines. In this mentioned position the looper is clear of all surrounding 90 obstructions and is as accessible as though completely removed from the machine. The looper device is actually increased in length for the time being, but is easily thrown up into normal position again when the same has 95 been threaded and the latch will snap behind the retaining pin 21, and again hold the arm in the body 15 in a rigid relation to itself. Under operating conditions, the arm is, of course, for all practical purposes rigid with 100

the body 15, whereas the hinging feature allows the easy threading which is so desirable.

Having now fully described my invention, I claim:

1. The combination with a sewing machine having fabric feeding means and sewing instrumentalities including a needle, there being a fabric table on said machine, a rockable looper shaft arranged parallel with said table, and a block secured upon said shaft to rock therewith, of a looper arm provided with a projecting looper and normally held rigid with said block in such manner as to be rockable with said shaft adjacent said needle, there being obstructions on either side of said looper arm confining the same to a relatively narrow space coincident with its general plane of movement, and means for releasing said arm and looper from normal position within said narrow space to a relatively more distant position with respect to said rockable looper shaft and said table through a plane of movement generally parallel with said looper and transverse to the axis of said shaft, in order to render said looper accessible for manual adjustments.

2. The combination with a sewing machine having a fabric support and a looper shaft disposed adjacent said support, of a plurality of looper blocks secured upon said shaft to be simultaneously rockable therewith, individual loopers supported upon said blocks to correspond with said needles, and means adapting said loopers to be individually swingable through parallel planes to temporarily increased distant positions relatively to said shaft so as to be relatively accessible with respect to said support.

3. The combination with a sewing machine having a fabric table and sewing instrumentalities including needles, and a rocker shaft arranged beneath said table, of a plurality of split blocks applied to said shaft in spaced relation so as to be individually removable and normally simultaneously rockable with the shaft, means to clamp and thereby secure said blocks to the shaft, individual loopers supported on said blocks to correspond with said needles and normally rock with said blocks and said shaft, said loopers being also independently displaceable with respect to said blocks so as to be rendered temporarily accessible relatively to said table for manual adjustments, at will.

4. In a sewing machine having a fabric table and a needle, a looper shaft having a block clamped thereon so as to be releasable therefrom, and normally swingable with said shaft, a looper arm pivoted on said block in such manner as to normally swing with said block and shaft, the looper arm being independently releasable to swing upon its pivot about an axis spaced in parallel relation to said shaft, and means to normally hold the

arm in association with said block, including a latch embedded in said block and protruding over the end thereof, there being a projection on said arm arranged to engage said latch, and there being also a looper disposed upon said arm in the plane of movement of said arm.

In testimony whereof, I, GUSTAV A. BOETTCHER have signed my name to this specification this fourth day of May, 1927.

GUSTAV A. BOETTCHER.
